CLAIM

(57) The ornamental design for the anchor float, as shown and described.

DESCRIPTION

FIG. 1 is a perspective view of an anchor float showing the new design, and

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view.

The anchor and line depicted in broken lines in FIG. 1 has been shown for the purpose of illustrating environment that forms no part of the claimed design.

The anchor float is an article that serves to transport a light weight anchor to a drop and securing location. In addition, it can be used as a marker buoy when a boater leaves the anchored location and wants to return to the same location.
